GASOLINE PUMP HOUSING

Bolling H. Sasnett, Jr., 775 Douglas Road NE.,
Atlanta, Ga. 30305

Filed Jan. 18, 1968, Ser. No. 10,215

Term of patent 14 years

Int. Cl. D9—04

U.S. Cl. D52—2

Fig. 1

Fig. 2

Fig. 3

FIG. 1 is a front-side-top perspective view of a gasoline pump housing embodying my new design;

FIG. 2 is a rear elevational view of the gasoline pump housing shown in FIG. 1; and,

FIG. 3 is a side elevational view of the other side of the gasoline pump housing shown in FIG. 1.

The dominant features of the design reside in the full line portions thereof.

I claim:

The ornamental design for a gasoline pump housing, substantially as shown and described.
